RUNNING BOARD

Herbert E. Bartsch, Chicago, Ill., assignor to Universal Railway Devices Company, a corporation of Delaware

Application January 23, 1939, Serial No. 252,373

12 Claims. (Cl. 105—457)

This invention relates to running boards such as used on top of box cars, and has for its principal object to increase the safety to trainmen and to reduce the cost of the original installation and repairs or replacements.

One feature of safety resides in making the tread concave or sloped upwardly and outwardly at the sides to prevent slipping and to give trainmen a greater feeling of safety both in standing with feet well apart crosswise to the board and in walking or running along the running board.

Another feature of safety resides in making the tread of reticulated or open-work metal, presenting corners or edges to prevent the trainman's feet from slipping in any direction; and the preferred material is expanded metal especially formed to arch those connecting parts between the uncut portions of the original sheet near their lower ends in order to get a greater length thereof in position to receive the trainman's feet, and therefore reduce the possibility of slipping or skidding.

To effect economy the running board is made in several sections assembled from each end of the car toward the middle, keyed with an intermediate section and made fast with a minimum (or greatly reduced number) of bolts so arranged that the whole has a natural tendency to remain together, but in which any section can be readily replaced.

Further objects and advantages of the invention will appear as the disclosure proceeds and the description is read in connection with the accompanying drawings in which

Fig. 1 is a perspective view of a portion of a box car showing the running board installed upon its roof;

Fig. 2 is a side elevation somewhat diagrammatic showing the adjacent ends of two sections of the running board and an intermediate section in position from which it is lowered into place, keying with the assembly;

Fig. 3 is an enlarged side elevation of adjacent ends of two sections assembled to a saddle on the car roof;

Fig. 4 is an enlarged perspective view of corner portions of two adjacent sections about to be assembled;

Fig. 5 is a perspective view of the frame of a running board section, the intermediate portion being broken away;

Fig. 6 is a perspective view of corner portions of the frame and a bolt fixture just prior to being brought together and made fast by rivets;

Fig. 7 is a plan view of one corner of one section of the running board;

Fig. 8 is a longitudinal section of one section or unit of the running board, the intermediate portion being broken away;

Fig. 9 is a transverse cross section of the running board;

Fig. 10 is a perspective view of an alternative form of frame;

Fig. 11 is a plan view of one corner of the running board having the modified form of frame;

Fig. 12 is a longitudinal section of adjacent ends showing a different means for fastening the sections together;

Fig. 13 is a transverse section of the running board having the modified form of frame;

Fig. 14 is a plan view of specially formed expanded metal preferably used for the tread of the running board;

Figs. 15 and 16 are sections taken on the lines 15—15 and 16—16 of Fig. 14;

Fig. 17 is a perspective view of an end section 30 of the longitudinal running board, made in a unit with the corresponding latitudinal running board;

Fig. 18 is a perspective view showing the parts of the frame work used in Fig. 17 displaced slightly to more clearly illustrate their form; and

Fig. 19 is a section taken on the line 19—19 of Fig. 17.

But these specific illustrations and the corresponding description are used for the purpose of disclosure only and are not intended to impose unnecessary limitations on the claims.

In Fig. 1, 10 indicates the roof of a box car, 11 the longitudinal running board made in sections and 12 the latitudinal portions of the running board.

Each section of the running board includes a frame, preferably as shown in Fig. 5, Sheet 2, including side beams 13, cross bars 14, and a sill 15. Each side beam is made of sheet metal and includes a web 16 (Fig. 6) forming the bottom chord and a flange 17 extending outwardly then upwardly at 18 and inwardly at 19, to form the top chord and also a means for receiving and fastening the edges of the tread.

Each cross bar 14 is of generally angle, or L-shape, in cross section and at each side has a flange 20 adapted to lie along the end of the web 16 and be secured to it.

At one end, in the preferred form, each corner is also equipped with a bolt fitting, generally indicated by A in Fig. 6, and including an L-head

55

21 and a bolt shank 22. The three parts shown in Fig. 6 are brought together and made fast by two rivets 23. Of course, it is not intended to exclude the use of welding and if that means 5 of fastening should be chosen it would doubtless be expedient to weld the flange 20 to the web 16 and weld the bolts to the vertical flange of the cross bar 14.

At the end opposite to that just described 10 each of the corners is provided with a short length of angle 24 (Figs. 5, 7 and 8) the beveled end 25 of which has a slot 26 and forms a seat adapted to rest upon a support (Fig. 3) shown as a Z-shaped bracket at 27 secured to the car roof by bolts 28. From this Fig. 3 it will be seen 15 that when two adjacent ends of running board sections are brought together the bolt 22 at the corner of one passes through the slot 26 at the corner of the other, through the support 27 and is made fast by nut 29.

This is the preferred form of connection between adjacent sections because of its simplicity and its natural tendency to remain assembled.

In placing the running board on the roof of the 25 car the sections, or units, will be assembled from opposite ends towards the middle, the end sections 30, Fig. 1, being placed first and fastened by braces 31, then other intermediate sections are installed in regular series towards the middle of 30 the car and finally a key section 32, Fig. 2, having bolts 22 at each end, is lowered in position and made fast.

With such a construction any section of the running board can be replaced by first removing 35 the key section and then the intermediate section, or sections, between the key section and the one to be replaced.

In the recommended practice shown in the 40 American Railway Association Manual Supplement, March 1, 1930, Plates 150, 151 and 163, at least six bolts are required at each saddle for the running board except at a splice when eight or more bolts are required. The saving of this preferred construction over the recommended practice 45 is very considerable in the matter of labor, both in installation and in repairs or replacements.

The tread 33 is of reticulated metal, the edges 50 of which are received between the portions 17 and 19 of the top chord of the side beams (Figs. 6 and 9). The portion 19 extends inwardly beyond the web 16 of each beam and is bent or struck down at 34 (Figs. 8 and 9) to enter openings in the reticulated metal and fasten the edges securely to 55 the beams.

In Fig. 9 it will also be noted that the sides, generally indicated by B, are sloped upwardly and outwardly. In this particular illustration there is a rise of one-half inch in four inches, but that is only illustrative, as is also the angular bends 35 in the cross bars 14 (Fig. 5). The intent is to make the tread somewhat concave, although in the main the upward and outward inclination will be most noticeable along the side edges, and it is a matter of indifference whether smooth 60 curves or polygonal shapes are used.

It has been found in practice that the upward 65 inclination at the sides prevents slipping and gives the trainman a greater feeling of security, whether he is standing with his feet well apart, as is customary, or is moving along the running board as the car sways, which it always does in travel. Generally speaking, the slopes should be 70 at right angles to the brakeman's leg when he is

standing spraddle-legged and facing one end of the car.

In this connection it will also be noted that by fastening the edges of the tread with the chord portions 19 nothing in the way of a trap 5 is formed at the side although there is a distinct edge over which the foot must ride before the actual footing can be lost.

In Fig. 10, Sheet 3, there is shown a modified form of frame, in which the sills 13 and 10 cross bars 14 are made in one piece from sheet metal, the joint at the ends of the strip being shown as a weld 36. This sort of frame lends itself to use with the fastenings disclosed in connection with Sheets 1 and 2, and both the modified and preferred form of frame lend themselves to use with the fastening means shown particularly in Fig. 12, Sheet 3, where the Z-shaped support 37 has a long top flange 38 upon which adjacent ends of running board sections rest 20 and are made fast by bolts 39, one at each corner, passing through openings 40 in the top flanges of the cross bars 14. By referring back to Fig. 5, where the openings 40 are also shown, it will be apparent how easily the preferred form 25 of frame lends itself to this modified mode of fastening which may be preferred by some railroad men.

By preference the tread is made of expanded 30 metal and that here shown corresponds to what is known in the trade as one and one-half inch No. 9, one and one-half inches being the distance between centers of the uncut portions 41 and 42, Figs. 7 and 11, and No. 9 being the gage 35 or thickness of the metal.

Expanded metal of this character can be bought in sheets of suitable width and length for sections of the running board, and with the mesh or connecting portions in the position shown, the corners presented to the trainman's foot, 40 make an excellent anti-slipping surface. Also, the stiffness crosswise to the running board is quite appropriate to the needs, being neither too yielding nor too stiff under the foot falls of the passing trainmen. Lengthwise, however, 45 such a sheet is too flexible and for that reason a sill 15 consisting of a flat bar, is placed in the middle between the cross bars 14. As shown, its ends 43 are turned at right angles and secured by rivets 44. This sill will give the necessary support against sagging lengthwise. 50

Conventional expanded metal is somewhat deficient in the length of the connecting portions presented at the surface, or what amounts to 55 the surface of the tread. Referring to Fig. 9, for example, the connecting portions 45, extending from an uncut portion 46 to an uncut portion 47, have a portion of their length too low to engage the trainman's foot. An improved 60 form of expanded metal, shown on Sheet 4, is to be preferred to the conventional form. By reference to that sheet it will be seen that the connecting portions 45 are arched upwardly near the uncut portions 46, thereby bringing a greater length at the general surface for contact with the trainman's foot.

The characteristics of the metal forming the frame will vary with the choice of the railroad's engineers and, of course, will vary somewhat with 70 the length of the sections. As shown, sections approximately five feet are contemplated and for such No. 12 sheet gage .109 thick is sufficient for the beams 13.

Where ordinary steel is used, any of the con- 75

ventional rust-proofing may also be used, such as galvanizing. If alloy steel is preferred, Corten, manufactured by United States Steel Company, will be found satisfactory.

5 Preferably each end section 30 is made in a unit with the corresponding latitudinal section 12, as shown on Sheet 5. By reference to Fig. 17, it will be seen that one of the side beams of the end section 30 is made in short lengths 50 joined 10 at right angles with the corresponding side beams 51 of the latitudinal section 12. Literally triangular pieces are cut out of the chord portions 17, 18 and 19, and the webs 16 are bent at right angles. Afterwards the chord portions are 15 welded, as indicated at 52.

A special cross bar 53 (with its flange 56 straight instead of being bent as shown at 20, Fig. 6) is riveted at 54 to the webs 16 of the short lengths 50 and forms the intermediate portion 20 of the side beam for the section 30, as well as one of the cross bars of the section 12.

25 A cross bar 14, like those used in the sections of the longitudinal running board, connects the remote ends of the beams 51 of the latitudinal running board 12.

The margins of the treads 33 of the joining sections are welded to the top of the special cross bar 53, at 55, by means of which the general surface of the treads is brought together with 30 a minimum of change in the footing.

I claim as my invention:

1. In a running board, a frame, a tread carried by the frame and extending longitudinally thereof, said tread being sloped upwardly and 35 laterally outwardly along the sides and extending from side to side of the frame.

2. In a running board, a frame, and an upwardly facing concave tread of reticulated metal extending longitudinally of, and from side to 40 side of, the frame.

3. A running board including a tread plate sloped outwardly and upwardly at each side and provided with numerous openings smaller than a man's shoe heel, bounded by sharp edges.

45 4. A running board including a plurality of sections, a support at the adjacent ends of two sections, one of the sections having slotted seats on the support and the other having downwardly directed bolts extending downwardly through 50 said slots and support for connecting the adjacent ends to the support.

5. A running board for railway cars and like conveyances comprising a tread having its side portions inclined upwardly and outwardly, and 55 means for supporting said tread with its axis in a substantially horizontal position whereby on rocking and rolling of the walk and on rounding curves the inclined portions of the tread will materially assist in preventing persons on the 60 walk from being thrown therefrom.

6. A metal running board comprising a tread of reticulated metal, a supporting frame for said tread of less width than the tread, said frame comprising side beams each having a top chord 65 extending laterally outwardly beneath, upwardly alongside and inwardly over the corresponding edge of the tread, cross bars connecting the side beams, and means integral with said chords for engaging said tread for holding the same in position on said frame.

7. A metal running board comprising a tread of reticulated metal, a supporting frame for said tread of less width than the tread, said frame comprising side beams each having a top chord 75 extending laterally outwardly beneath, upwardly

alongside and inwardly over the corresponding edge of the tread, and bent downwardly to enter marginal openings in the tread, and cross bars connecting the side beams.

8. A metal running board comprising a tread 5 of reticulated metal, a supporting frame for said tread of less width than the tread, said frame comprising side beams each having a top chord extending laterally outwardly beneath, upwardly alongside and inwardly over the corresponding 10 edge of the tread, the inwardly extending portion of the chord being wider than the outwardly extending portion and being bent downwardly into marginal holes in the tread, and cross bars connecting the side beams.

15 9. A running board for railway cars and the like comprising two end sections secured to the ends of the car, respectively, each section comprising a frame, a tread member secured to said frame and a bracket rigidly secured to the inner 20 end of each frame and extending inwardly and

provided with an aperture, a connector section and a plurality of intermediate sections between said connector and end sections, each intermediate section comprising a frame and a tread mem- 25

ber secured to said frame, each of said intermediate sections having rigidly connected thereto a downwardly extending bolt at one end and a bracket having an aperture at the other end

thereof, the aperture being on the inner end of 30 each intermediate section, supporting brackets beneath said first-named brackets rigidly secured in position and having apertures therethrough in alignment with the apertures in said brackets

for receiving said bolts, said connector section 35 comprising a frame, a tread portion carried by said frame, and a bolt rigidly connected to each end thereof and depending therefrom for engaging the apertures in the brackets of adjacent intermediate sections whereby after the end and 40

intermediate sections have been secured in position, the connector section may be lowered in position between the intermediate sections at each end portion of the car with the bolts extending through the aligned apertures in brackets 45 of adjacent sections and bracket supports.

10. A running board including two sections substantially in alignment and spaced apart endwise and having slotted seats at the adjacent ends, a bracket beneath each seat secured to the 50 roof of a car, each bracket having an opening in vertical alignment with the slot in the corresponding seat, and an intermediate section having downwardly directed bolts rigidly secured thereto and adapted to be received in the slots in 55 said seats and extending through said openings in said brackets.

11. A running board comprising a pair of sections spaced apart, a bracket beneath the inner end of each section secured to the roof of a car, 60 each bracket having a vertical opening therethrough, each section having connecting members rigidly attached to their inner ends and

provided with slots in alignment with the openings in said brackets, an intermediate section 65 having rigidly secured thereto depending bolts for engaging said slots and openings and fastening means for said bolts whereby said sections may be assembled by first rigidly securing said pair of sections in alignment in spaced position 70

and then lowering the intermediate section in position between the first-named sections with the bolts extending through said slots and openings so that even though the fastening means become lost, said intermediate section will be 75

maintained in lowered position in alignment with the first-named sections by said bolts and the force of gravity.

12. In a running board, a frame comprising side beams spaced apart, cross bars connecting the ends of said side beams, a sill connected to the central portions of said cross bars, said cross

bars having their upper surfaces inclined upward and outward at each side portion of the frame, and a tread conforming to the upper surfaces of said beams, sill and cross bars and rigidly secured to said side beams.

HERBERT E. BARTSCH.
